UNITED STATES PATENT OFFICE.

FRED N. McDAVITT AND ARTHUR W. McDAVITT, OF LA PLATA, MISSOURI.

MAIL-BAG CATCHER AND DELIVERER.

SPECIFICATION forming part of Letters Patent No. 645,232, dated March 13, 1900.

Application filed October 14, 1899. Serial No. 733,648. (No model.)

To all whom it may concern:

Be it known that we, FRED N. McDAVITT and ARTHUR W. McDAVITT, citizens of the United States, residing at La Plata, in the 5 county of Macon and State of Missouri, have invented a new and useful Improvement in Mail-Bag Catchers and Deliverers, of which the following is a specification.

This invention relates to devices to be 10 erected at the side of a railway-track and on a mail-car for the purpose of delivering mail-bags to and from the car and catching the bags thus delivered, the object being to provide an outfit of this class of simple, strong, 15 durable, and efficient construction.

In the drawings forming a part of this specification, Figure 1 is a perspective view illustrating that part of the invention which is erected at the side of the track with a mail- 20 bag suspended ready to be caught on the car and the parts in position to catch a bag from the car. Fig. 2 is a top plan view, on an enlarged scale, of the receiving-hook and its 25 guide and support, the post being shown in section. Fig. 3 is a fragmentary detail perspective view of the outer end of the hook. Fig. 4 is a detail sectional view on the plane indicated by the broken line 4 4 of Fig. 2. Fig. 5 is a similar view on the plane indicated 30 by the broken line 5 5 of Fig. 2. Fig. 6 is a view in elevation of the devices for suspending a bag from the car, the arms being extended outward from the car. Fig. 7 is a 35 similar view of the same parts with the arms folded into the car. Fig. 8 is a detail perspective view of one of the hooks by which the mail-bag is secured between the arms. Fig. 9 is a central vertical sectional view of the 40 same. Fig. 10 is a detail perspective view of the catch for holding the bag-holding arms extended from the car-door.

Like numerals of reference mark the same parts wherever they appear in the several figures of the drawings.

Referring to the drawings by numerals, 10 indicates one rail of a railroad, and 11 12 ties upon which the rail rests, the latter extending some distance laterally beyond the former and supporting a platform 13, upon which is 15 mounted a post 14, either solid or hollow and of any suitable material, but preferably a metal tube, as shown, rigidly held in upright

position by means of braces 15. Upon the post a short distance above the ties is secured a platform 16, stiffened by braces and provided with a step-ladder 17 with hand-rail 18. Just above the platform 16 an arm 19 is pivotally secured to the pole and adapted to swing outward toward the rail, as in Fig. 1. Near the top of the pole is pivoted a second 60 arm 20, having a weighted projecting end 21 beyond the pivot; which end is connected to the arm 19 on the opposite side of the post, as at 22, whereby when one arm is moved the other must be moved with it and whereby 65 both arms are maintained in horizontal position, as in Fig. 1.

At the outer ends of each arm 19 and 20 are eyes 23 24, in which are attached hooks 25 and 26, (shown in detail in Figs. 8 and 9,) each 70 composed of a flat piece of metal forming a body 27, having an opening 28 to receive a ring or link 29 for attaching it to the eyes of the arms and a longitudinal central notch 30 and a spring 31, attached to the body by a nut 75 32, coiled at 33 and normally resting in the notch 30. To-suspend a mail-bag in the position shown in Fig. 1 ready to be caught by the catcher on the car, the rings 34 of the bag are engaged in the positions illustrated in 80 Fig. 1 and in dotted lines in Figs. 8 and 9, where they are yieldingly held by the springs 31, subject to be drawn off the hook by the catcher of the car. When the arms are relieved of the weight of the bag, the weighted 85 end 21 of arm 20 will fall, raising arm 20 to a substantially-vertical position and permitting arm 19 to fall to a similar position alongside of the post.

Upon the pole a little above the center of 90 the space between arms 19 and 20 is secured a metallic semicircular bar 35, secured by a pin 36 and stiffened by braces 37, the pin passing through a ring on the bar which encircles the post and through the post, as best 95 shown in Fig. 5. Above the ring 35 on the post is a clamp in which is pivoted an arm 38, which projects radially beyond the edge of the semicircular bar and at its outer end is bent in a horizontal plane into hook form, as 100 at 39, as most clearly shown in Figs. 2 and 3. On the hook is formed a lug 40, upon which is coiled the central part of a spring 42, one end 43 of which

bears against the outside of the hook, while the other end 44 reaches diagonally across the throat of the hook and bears against the inside thereof, the normal tendency of the spring being to remain yieldingly in this position.

In a lug 45 in the inner edge of the bar 35 is a horizontal rod or arm 46, normally forced toward the point of the hook by a spring 47, 10 which tends to hold it under the horizontal arm of an elbow-lever or trigger 48, pivotally secured to the outer surface of bar 35, the vertical arm of the trigger bearing normally against the hook-arm 38 and holding it in position against an upwardly-projecting stop or lug 49 on the end of bar 35, as shown in Figs. 2 and 4.

50 50 indicate a pair of eyes or staples secured on the face of a door or jamb 51 of the 20 car, in which is slidably and rotatably mounted a vertical bar 52, the ends of which are bent at right angles, as at 53 54, to form arms to support a bag in position to be caught on the stationary catcher.

25 55 indicates an intermediate eye also secured to the door, in which the bar 52 is also mounted, and 56 a spring coiled around the bar and having its lower and upper bearings, respectively, against the eye 55 and a collar 30 57, secured to the bar, the normal tendency being to raise the bar 52 and arms 53 and 54. A second spring 58, coiled around bar 52, has one end secured to the car at 59 and the other end to an arm 60 on bar 52, the normal 35 tendency being to hold the arms 53 and 54 in the car and parallel with the track. In this position, as illustrated in Fig. 7, the arm 53 rests above the horizontal arm 61 of a keeper 62, (shown detached in Fig. 10 and

40 in combination in Fig. 7,) said keeper being secured to the car and provided with a vertical arm 63 at the outer end of horizontal arm 62. The arms 53 and 54 have eyes 64 65 at their ends, to which will be attached hooks 45 to engage the top and bottom rings of a mail-bag, which will be hung thereon while the arms are in the position of Fig. 7. The arms are now swung out to positions at right angles to the car, as shown in Fig. 6, the weight

50 of the bag causing arm 53 to fall between the vertical arm 63 and be locked in its outer position as long as the weight of the bag is upon it. When the bag is caught, the arm 53, relieved of its weight, will be raised above arm 55 61 of keeper 62 by spring 56, thus leaving it free to be turned in, which will be done by spring 58, the arm 60 acting as a stop to prevent the bar 52 from being rotated far enough to carry arms 53 and 54 beyond their inner 60 position parallel with the track.

To suspend a mail-bag on the arms 19 and 20, the carrier mounts the platform 16 and draws down arm 20, which by reason of the chain connection raises arm 19, when the bag 65 can be hooked up, as before described. A hook or catcher outfit similar to that shown in Fig. 1 may be mounted in the car, and when the

car, with a bag suspended on arms 53 and 54 and its catching mechanism in position, reaches the stationary crane with a bag suspended between arms 19 and 20 the hook on the car will take the bag from arms 19 and 20 and the hook on the stationary outfit will take the bag off arms 53 and 54 without the necessity of throwing or otherwise handling 70 the bags. When a bag to be caught enters the throat of the hook 39, it strikes arm 46 and swings it around on its pivot, releasing trigger 48 and permitting arm 38 and hook 39 to swing around on semicircular bar 35 to a 80 position parallel with or away from the track, where it is supported by bar 35. The impetus of the bag throws it farther into the throat of hook 39, pressing back end 44 of spring 42, which holds it against dropping out of the 85 hook.

From the foregoing it will be seen that we have provided simple, strong, cheap, durable, and efficient means for performing all of the 90 functions of a mail-bag catcher and deliverer, and while we have specifically described means for carrying out our invention it will be readily understood many slight changes 95 might be made in such constructions without departing from the limit and scope of the invention.

Having thus fully described our invention, what we claim as new, and desire to secure by Letters Patent of the United States, is—

1. In a mail-bag catcher and deliverer, a 100 suspending-hook consisting of a flat body having a longitudinal notch and provided with means for connecting it to the crane-arms, in combination with a spring secured to the flat body and normally projecting through the 105 notch, substantially as described.

2. In a mail-bag catcher and deliverer, a platform secured on the projecting ends of the ties and a metal tubular post mounted thereon and braced thereto, in combination with 110 an upper platform secured and braced to the post, a step-ladder connecting the two platforms, and a projecting pole of the ladder extending above the upper platform and forming a hand-rail, substantially as described. 115

3. In a mail-bag catcher and deliverer, the combination with a post of a semicircular bar secured thereto in a horizontal position and having a stop at each end, an arm pivotally mounted on the post and supported by 120 said bar, means for locking the arm to the bar and a bag-catching hook at the outer end of the bar, substantially as described.

4. In a mail-bag catcher and deliverer, the combination with a post of a semicircular bar 125 secured thereto in a horizontal position, an arm pivotally mounted on the post and supported by said bar, a hook at the end of the bar, a trigger to engage the bar to hold it against turning on the post, and a spring-actuated arm pivoted to the semicircular bar and normally holding the trigger in position, said bar being in the path of a bag entering the throat of the hook, substantially as described. 130

5. In a mail-bag catcher and deliverer, the combination with a post of an arm pivoted thereon, a hook at the outer end thereof; an elbow-lever trigger having its vertical arm adapted to hold the bar against turning and a bar holding the trigger in position and located in the path of a mail-bag entering the throat of the hook, substantially as described. 30
5. In a mail-bag catcher and deliverer, a hook for catching the bags provided with a lug on its outer side a pin in said lug and a spring-bar having its central portion coiled about the pin, the outer end of the spring-bar beating against the outside of the outer arm 15 of the hook and the inner end against the inner side of the inner arm of the hook, substantially as described.
6. In a mail-bag catcher and deliverer, a rotatable bar mounted in the car-door and having its upper and lower ends bent at right angles forming arms upon which to suspend a mail-bag, of a keeper and latch adapted to lock the arms extended when weighted with a mail-bag, a spring for normally holding the arms raised above the keeper and latch, and a spring with a normal tendency to turn the arms into the car, substantially as described. 35
6. In a mail-bag catcher and deliverer, the combination of three staples or eyes secured to the car in a vertical line, a vertical bar slidably and rotatably mounted therein, suspending-arms projecting at right angles from the ends of the vertical bar, a stop-arm projecting from the vertical bar at right angles 40 to the suspending-arms, a collar on the vertical arm, a latch or keeper secured to the door and having a horizontal and vertical arm, a spring coiled about the vertical bar above a staple and below the collar, and a second 45 spring coiled about the vertical bar having one end secured to the car and the other to the stop-arm, substantially as described.
7. In a mail-bag catcher and deliverer, the combination of a vertically slidable and rotatable bar mounted in the car-door and having its upper and lower ends bent at right angles forming arms upon which to suspend a mail-bag of a keeper or latch adapted to lock the arms extended when weighted with mail-bag, and a spring adapted to raise the arms above the keeper when released of the weight of the bags, substantially as described. 50
8. In a mail-bag catcher and deliverer, the combination of a vertically slidable and ro-
